WINDER

Burt A. Peterson, Rockford, Ill., assignor to
 Barber-Colman Company, Rockford, Ill., a
 corporation of Illinois

Application September 20, 1935, Serial No. 41,353

4 Claims. (Cl. 28—26)

This invention relates to winders, as, for example, ball and beam warpers, and more particularly to means for causing the yarn to be wound under pressure and for counteracting any tendency to make the yarn mass eccentric or tapering.

The specific embodiment herein shown of the invention is an improvement upon the mechanism disclosed in the Colman Patent No. 1,366,447, dated January 25, 1921. In that mechanism a weight 427, through a system of levers, pressed the yarn mass against the winding drum. Since the leverage exerted by the weight was not variable, as much pressure was applied by the weight to a full warp beam as to an empty beam; consequently the pressure exerted upon a full beam as compared with the pressure placed upon an empty beam, was greater by an amount equal to the weight of the yarn mass. It is desirable that all portions of the yarn mass shall be wound under approximately constant pressure. The object of the present invention is to provide a construction that will keep the pressure approximately constant during the winding of the entire yarn mass.

25 In the accompanying drawings:

Figure 1 is a fragmental right-hand end elevation of a beam warper embodying the present improvements.

Fig. 2 is a fragmental front elevation of the 30 warper.

Fig. 3 is a fragmental left-hand end elevation of the warper.

Fig. 4 is a detail view of a ratchet mechanism comprised in the present embodiment of the 35 invention.

The drawings show a warp beam B as operatively mounted in the warper, said beam comprising a barrel b, heads b', and trunnions b². The beam is supported and rotated by means 40 of a friction drum 1 rotatably mounted in the framework of the warper and driven by any preferred means. The beam B is supported with its yarn mass in peripheral contact with the periphery of the drum 1 by means of two arms 2 and 3 which are pivoted in the warper framework upon the axis 4. The trunnions b² may 45 be connected to the arms 2 and 3 in any desired manner.

The beam is pressed against the friction drum 50 1 by means including two screw rods 5 that extend through slots in said arms. Each rod 5 is threaded through a nut 6 having on opposite sides studs 7 that lie in elongated openings 8 in the arms. Each screw rod 5 is rotatably mounted 55 in a yoke or coupling member 9 and held against endwise movement with relation to the yoke. The yokes 9 are pivotally mounted upon a shaft 10 extending from side to side of the warper. The shaft 10 is rotatably mounted in the forward 60 arms of two levers 11, said levers being pivoted

in the warper framework upon the axis 12. The rear arms of the levers 11 are connected by means of links 13 to crank arms 14 fixed upon a rock shaft 15 journaled in the warper framework. A coiled contractile spring 16 is connected at its lower end to the left-hand crank arm 14 and is anchored at its upper end to a rearward extension 17 secured to the beam arm 3. It will be seen that the spring 16 exerts force to lift the rear arms of the levers 11 and thus draw 10 the beam arms 2 and 3 down to hold the barrel of the beam B pressed against the friction drum 1.

In order to allow the beam to rise as yarn is wound upon the barrel b' the screw rods 5 are rotated in the direction to cause the nuts 6 to 15 travel upwardly on the screw rods. For this purpose a bevel gear 18 is fixed to the lower end of each screw rod 5, said gears meshing with bevel gears 19 fixed upon the shaft 10. It will be seen that rotation of the shaft 10 will cause the screw 20 rods 5 to be simultaneously rotated.

The shaft 10 is rotated in the direction to produce upward movement of the nuts 6 by means comprising a roller ratchet of the silent type. This ratchet may be of any common or desired 25 construction. Herein, it consists of a disk 20 fixed on the left-hand end of the shaft 10, and a coacting roller 21 carried by a member 22 which is virtually a bell crank. In the opposite sides of the member 22 are slots 23 through which the 30 trunnions 24 of the roller 21 extend. The member 22 is pivotally supported upon the shaft 10 and is arranged to be oscillated by means of a crank disk 25 and a pitman 26. The crank disk 25 is rotatably mounted in the warper frame- 35 work and is driven from the shaft of the friction drum 1 through gears 21. Counterclockwise movement of the member 22, as viewed in Figs. 3 and 4, is idle and produces no movement of the disk 20. Clockwise movement of the member 22 40 causes the roller 21 to frictionally engage the disk 20 and thus cause the shaft 10 to turn, except when the roller 21 is displaced from the lower ends of the slots 23 by means to be now described.

An arm 28 rigidly secured to the rock shaft 15 has a forked forward end 29 which underlies the trunnions 24 of the roller 21. When the arm 28 is in the position shown in Fig. 4, its forked forward end does not interfere with the 50 roller 21, but when said arm rises so as to lift the trunnions of the roller 21 in the slots 23 the roller is prevented from clutching the disk 20 to the bell crank member 22 and consequently 55 clockwise movement of the member 22 imparts no movement to the disk 20 and the shaft 10.

Any desired means may be employed to damp the vibrations of the levers 11, as for example, a dashpot 30, the plunger of which is connected 60

to a crank arm 31 which is rigid with the rock shaft 15.

Means is provided for manually rotating the screw rods 5 to raise and lower the beam arms 2 and 3 when the beam is to be removed from the warper and when an empty beam is to be lowered into place upon the friction drum 1. Said means comprises a squared stud 32 adapted to receive a crank (not shown), said stud being 10 connected to the shaft 19 by means of a sprocket chain drive 33, as described in said Patent No. 1,366,447.

In operation, the friction drum 1 is rotated to revolve the beam B in the direction indicated by 15 the arrows in Figs. 1 and 3 to wind the warp threads upon the beam. The spring 16 presses the yarn mass on the beam with the desired pressure against the drum 1. As the yarn mass increases in diameter, the arms 2 and 3 are forced 20 upwardly against the tension of the spring 16, thus lifting the screw rods 5 and causing the levers 11 to turn, the rear ends of said levers moving downwardly against the tension of the 25 spring 16. Such turning movement of the levers 11 causes the forward end of the stop arm 28 to move downwardly. When said stop arm has 30 swung downwardly so far as to be free of the trunnions of the roller 21, said roller becomes effective to grip the disk 20 so that the pitman 24 is enabled to impart one or more movements 35 to the disk 20 and the shaft 19. The screw rods 5 are thereby turned through a partial revolution in the direction to lower said rods. Such movement of the screw rods enables the spring 40 16 to raise the rear arms of the levers 11 and to lift the stop arm 28, thus causing suspension of operation of the roller ratchet 20, 21. The mechanism thus operates intermittently to produce a succession of slight adjustments of the 45 connection between the beam arms 2 and 3 and the pressure-applying means as the yarn mass increases in diameter.

It will be seen that as the beam fills and the beam arms 2 and 3 rise, the rearward extension 45 17 descends, thus reducing the tension of the spring 16. The increase in the weight of the 50 yarn mass is thus compensated by reduction in the tension of the spring 16 so that the pressure to which the yarn mass is subjected throughout the operation of filling the beam is approximately constant.

Although the present embodiment of the invention has been described in considerable detail, it will be understood that the invention is 55

not limited to such details except to the extent indicated in the appended claims.

I claim as my invention:

1. A winder having, in combination, a friction driving drum, means for supporting a yarn container with its yarn mass in peripheral contact with the driving drum, and means for pressing the yarn mass against the drum, said pressing means including yarn-controlled means for automatically reducing the pressure to compensate for the increased weight of the yarn mass as the container fills, whereby to render the pressure of the yarn mass against the drum approximately constant. 10

2. A warper having, in combination, a friction driving drum, means for supporting a yarn container with its yarn mass in peripheral contact with the driving drum, and means for pressing the yarn mass against the drum, said means including a spring, an anchorage for the spring, 15 and yarn-controlled means for automatically adjusting the anchorage to reduce the tension of the spring as the yarn mass grows. 20

3. A warper having, in combination, a supporting framework, a friction driving drum rotatably mounted in the framework, two arms pivoted in the framework for supporting a warp beam with its yarn mass in peripheral contact with the drum, means connected to said arms for pressing said yarn mass against the drum, said 25 means including a spring, a rearward extension on one of said arms to which said spring is anchored, and yarn-controlled means for adjusting the connection between said arms and the pressing means as the beam fills and said arms 30 rise, the lowering of said rearward extension as the arms rise causing reduction in the tension of the spring to compensate for increase in the 35 weight of the yarn mass. 35

4. A warper having, in combination, a supporting framework, a friction driving drum rotatably mounted in the framework, two arms pivoted in the framework for supporting a warp beam with its yarn mass in peripheral contact with the drum, means connected to said arms for 40 pressing said yarn mass against the drum, said means including a spring, an anchorage for the spring, and yarn-controlled means for adjusting the connection between said arms and the pressing means as the beam fills and for adjusting the 45 anchorage to reduce the tension of the spring to 50 compensate for increase in the weight of the yarn mass. 50

BURT A. PETERSON.
